UNITED STATES PATENT OFFICE.

WILLIAM J. CANNON AND ALFRED HERMANY, OF CHICAGO, ILLINOIS.

COUPON RAILROAD-TICKET.

1,160,377.

Specification of Letters Patent.

Patented Nov. 16, 1915.

Application filed September 9, 1913. Serial No. 788,806.

To all whom it may concern:

Be it known that we, WILLIAM J. CANNON and ALFRED HERMANY, citizens of the United States, and residents of Chicago, county of Cook, and State of Illinois, have invented 5 certain new and useful Improvements in Coupon Railroad-Tickets, of which the following is a full, clear, and exact description.

The invention relates to so-called coupon 10 or interline tickets for transportation over an initial line of road and connecting lines, and seeks to provide a simple, improved form which may be easily read and understood and in which the execution or issuing 15 of the ticket may be readily and accurately effected to show the complete route or journey upon each of the passage coupons and upon the agent's stub.

The invention consists in the features of 20 novelty hereinafter set forth, illustrated in the preferred form in the accompanying drawings and more particularly pointed out in the appended claims.

In the drawings, Figure 1 shows the 25 agent's stub and the first three coupons of one form of the improved ticket. Fig. 2 shows the last three coupons of the ticket and the contract portion. Fig. 3 illustrates another form of the improved ticket with 30 the contract portion thereof omitted.

In the improved ticket, the several coupons which are valid for different portions 35 of the journey are connected together at their vertical side edges and extend from left to right lengthwise of the ticket in the order of their use. Such coupons necessarily vary in number, in accordance with the number of links or junctions between the starting point and destination.

40 In the form shown in Figs. 1 and 2, there are six coupons, 1, 2, 3, 4, 5 and 6 which are adapted to be used from any starting point upon a railroad running into Council Bluffs to a destination upon any one of a number 45 of lines running out of Buffalo. These coupons are formed by dividing the ticket by a number of vertical, indented or weakened lines 7 which form the vertical side edges of the several coupons. These several coupons 50 are arranged from left to right lengthwise of the ticket in the order of their use, and the usual agent's stub 8 is formed at the left hand end of the ticket, being separated from the first passage coupon by one of the 55 weakened lines 7. The contract portion 9

of the ticket is arranged at the right hand end, being separated from the last coupon by a vertical line 10 which, however, is not a weakened line. The reading matter upon all of the coupons and upon the contract 60 portion, and the principal portion of the reading matter upon the agent's stub is horizontally disposed. When the ticket is issued, the agent's stub is detached. The parts of the ticket are thus arranged in natural reading order or from left to right lengthwise of the ticket and in the order of sequence in which the several coupons are used. The several coupons are provided with different 65 captions which extend across the top of the ticket, where they readily catch the eye, and which clearly indicate the different portions of the journey over which the respective coupons are valid. These captions are preferably emphasized, for example, by 70 printing the same in heavy, bold faced type, as in the ticket illustrated. Thus, as clearly indicated, in captions of the several coupons in the form shown in Figs. 1 and 2, the first 75 coupon is good from a station on the Inter-line Railway to the first junction point, Council Bluffs, the second coupon is good from Council Bluffs to Chicago, the third for the omnibus transfer at Chicago, the fourth from Chicago to Buffalo, the fifth 80 for the omnibus transfer at Buffalo and the 85 sixth from Buffalo to the destination.

The agent's stub and each coupon contains a list of the connecting lines which are preferably arranged in a single, vertical column and are consecutively numbered, 90 as shown. If the ticket is intended to read through more than one junction or gateway, the list of lines on each coupon and on the agent's stub is divided into separate 95 groups or sections in accordance with the number of junctions, and these groups of lines are arranged in the proper geographical order. For example, the ticket shown in Figs. 1 and 2 reads through three junctions 100 or gate-ways, namely, Council Bluffs, Chicago and Buffalo, and the list of lines upon the agent's stub and on the several coupons is divided into three groups *a*, *b* and *c*. The first group *a* contains six lines which extend 105 from Council Bluffs to Chicago. The next group *b* contains five lines extending from Chicago to Buffalo and the last group *c* contains eight lines running out of Buffalo, and the ticket can be issued to a destination upon 110

- any one of these lines in the terminal group *c*. Each coupon and the agent's stub also indicates adjacent the groups of lines, the route over which each group extends. For 5 example, in the form shown, the words "Routing to Chicago", "Routing to Buffalo" and "Routing to destination" are arranged in a column parallel to the vertical column of connecting lines and opposite the respective groups. At the bottom of the list of 10 lines the agent's stub and the several coupons are provided with a space *d* in which the destination may be indicated. In the form shown in Figs. 1 and 2, this space is 15 blank and the destination is written with pen and ink in this blank space when the ticket is executed or issued. Below the space *d* the agent's stub and each coupon is provided with properly designated spaces *e* and *f* for indicating, respectively, a "half" 20 or "2d class" passage, and an indicating space *g* marked "B. C." for receiving the punch mark which cancels the ticket for baggage.
- 25 Each coupon and the agent's stub is also preferably provided with a vertical column of stars or similar punch guides corresponding to the list of lines thereon. The consecutive numbers and the punch guides or 30 stars are arranged adjacent the right hand edge of the agent's stub and are alternately arranged adjacent the left hand and right hand side edges of the succeeding coupons. The indicating spaces *e*, *f* and *g* are also 35 similarly arranged. In executing the ticket, it is folded about the lines 7 commencing at the left hand end, each coupon being folded beneath the preceding one, and the first coupon being folded beneath the agent's stub.
- 40 The punch guides and indicating spaces *e*, *f* and *g* will then all register along the right hand marginal folds and beneath the right hand edge of the agent's stub. The lines selected in the different groups can then be 45 readily indicated by a single punching operation in each group and the other details can be indicated in the spaces *e* and *f*, if necessary. Similarly, the entire ticket can be canceled for baggage by a single punching 50 operation. It should be noted that the spaces for the punching operations are arranged closely adjacent the margin of the ticket when it is folded, so that a single die punch, such as an ordinary L or O punch 55 can be used and long multiple die punches need not be employed. In this way, the different connecting lines over which the ticket is issued and the other details are clearly indicated on the agent's stub and each of 60 the different coupons.
- 65 The caption at the top of the first coupon contains the name of the issuing line and its junction, and the caption of the other coupons indicates the portions of the journey for which such coupon is valid, and also

contains a reference to the connecting lines designated or selected by the punch marks. That is to say, in the form of ticket shown in Figs. 1 and 2, the caption of coupon No. 2 contains the names of the junctions Council Bluffs and Chicago between which the coupon reads and a reference to the selected line in the first group. Similarly, the captions of coupons 4 and 6 clearly indicate the points between which these coupons read 75 and contain references to the selected line in the second and third groups, respectively. Preferably, the particular group of lines to which each of the coupons 2, 4 and 6 relate is emphasized, for example, as shown, by 80 printing the same in bold faced type; and the respective groups upon these coupons are designated in the caption and in the body of the coupon by the words "Section 1", "Section 2" and "Section 3".

Coupons 3 and 5, as stated, are for omnibus transfers at Chicago and Buffalo and, as indicated in the caption, are good only if the connecting lines at Chicago and Buffalo occupy different stations and are void if they 90 occupy the same station. Preferably, these transfer coupons also contain a column containing the words in bold type "Transfer coupon not good on trains".

The agent's stub and the several coupons 95 are each provided at its lower portion with a space *h* for the form number of the ticket, a space *j* for the ticket number, and also with the name of the issuing line. The agent's stub is also provided along its left hand margin with brief instructions for executing or issuing the ticket, these printed instructions being disposed vertically upon the stub. At the top the stub is provided with spaces for the route numbers and the 100 fare. By consecutively numbering the connecting lines, the route may be very easily and briefly summarized. For example, the words "Form 5000—1—9—15" would be the 105 route numbers for a trip from any station 110 on the initial line to Council Bluffs, thence over the Burlington route to Chicago and the Michigan Central Railroad to Buffalo, and thence over the Erie Railroad to the destination.

The contract portion 9 contains the usual contract and has at its lower portion the spaces *d*, *e*, *f*, *g*, *h*, and *j* similar to the corresponding spaces upon the agent's stub and passage coupons. It also contains the usual 120 date staff *k* at its right hand margin which, when properly punched, indicates the limit of the ticket. When there is an odd number of coupons in the ticket, for example three, as shown in Fig. 3, the contract portion is 125 not folded for punching the details of the route, but with an even number of coupons, such as shown in Figs. 1 and 2, the contract portion is folded beneath the last coupon about the line 10. In such cases, the left 130

hand margin of the contract portion is preferably provided with a row of stars or like punch guides to indicate the nature of the punching in that margin and the indicating spaces *e*, *f* and *g* are also arranged on the left hand margin, so that they are punched with the coupons and by a single punching operation for each detail indicated. If desired, an extra dummy or blank coupon or 10 section may be inserted between the agent's stub and the first coupon in all tickets having an even number of coupons, so that the folding and punching of the left hand margin of the contract portion may be avoided. 15 The form shown in Fig. 3 is similar to that shown in Figs. 1 and 2, except that the ticket reads over the issuing line to a single junction point, namely, Chicago and thence from Chicago to a destination over a number 20 of connecting lines, thirteen in number in the form shown. The ticket also contains a list of printed destinations beneath the list of lines and having punch guides. This list contains the names of the principal points 25 upon the connecting lines and in a large number of instances, avoids the necessity of writing the destination upon the coupons with pen and ink.

The arrangement of the coupons or sections is in horizontal order and extends lengthwise of the ticket from left to right, commencing with the agent's stub, followed by the coupons for the initial and succeeding portions of the journey arranged in the 30 sequential order of use and ending with the contract portion at the right hand end of the ticket. In this way all of the details of the ticket are presented in their natural order to the eye of the agent, passenger, conductor 35 and others having to do therewith, when the ticket is either folded or extended. By reason of this horizontal arrangement while the details to be indicated register when the ticket is folded for punching, such details 40 are arranged in the same relative vertical order on each coupon or section, instead of in alternately reversed order, as is the case when the coupons of such tickets are vertically arranged. The details of the tickets 45 are so arranged, as stated, that when folded the stars or punch guides are at the right hand margin or edge of the folded ticket. The latter is then in the most convenient position for indicating the details with a punch 50 held in the right hand. At the same time, the instructions and other reading matter upon the agent's stub is clearly visible, so that the ticket can be quickly and accurately executed, the details being punched in order from top to bottom. By having the date staff at the right hand margin of the 55 contract portion, it also can be readily and quickly punched to indicate the time limit of the ticket.

60 It is obvious that numerous changes may

be made in the details set forth without departure from the essentials of the invention as defined in the claims.

We claim as our invention:—

1. An interline coupon ticket comprising 70 a plurality of coupons connected along their vertical side edges and arranged from left to right lengthwise of the ticket in geographical order of use, each of said coupons containing the same list of connecting lines 75 arranged in a single vertical column and in the same relative order on each coupon, said list of lines being divided into separate groups arranged in geographical order with the routing of each group associated therewith, each coupon having a vertical column 80 of consecutive numbers for designating the separate lines of the list thereon and an associated vertical column of punch indications, said columns of numbers and punch 85 indications being alternately arranged at the right and left hand margins of the coupons and adapted to register along one margin when the ticket is folded, said coupons having different captions arranged in horizontal alinement across the top of the ticket, the caption of the first coupon containing the name of the issuing line and its junction and the caption of each of the other coupons containing the names of the points between 90 which the coupon is good together with a reference to the group of lines and to the selected line in the group over which the coupon is valid, substantially as described.

2. An interline coupon ticket comprising 100 a plurality of coupons connected together in geographical order of use, each of said coupons containing the same list of connecting lines divided into separate groups arranged in geographical order with the routing of each group associated therewith, each of said lines being designated on each coupon by a distinctive character and each of said coupons bearing the same form number, the name of the issuing line and a suitably designated space for receiving the name 105 of the destination.

3. An interline coupon ticket comprising an agent's stub and a plurality of coupons connected along their vertical side edges in 115 horizontal alinement from left to right and in geographical order of their use lengthwise of the ticket the printed matter on said coupons being horizontally disposed, said agent's stub and each of said coupons bearing the same form number and the same list of connecting lines arranged in a single vertical column with corresponding vertical columns of punch indications and of consecutive 120 numbers for designating the separate lines of the list, said vertical columns of numbers and of punch indications being alternately arranged along the right and left hand margins of the coupons and adapted to register along the right hand margin of 125 130

the agent's stub when the ticket is folded beneath the same, said coupons having different captions extending in horizontal alinement across the top of the ticket, the 5 caption of the first coupon containing the name of the initial line and its junction and the caption of the other coupons containing the names of the points between which the coupon reads and a reference to the selected 10 line over which the coupon is valid, substantially as described.

4. An interline coupon ticket comprising an agent's stub and a plurality of coupons connected together in geographical order of 15 use, said agent's stub and each of said coupons bearing a list of connecting lines together with vertical columns of punch indications and of consecutive numbers for designating the separate lines of the list, 20 said vertical columns of numbers and of punch indications being arranged to register at the margin of the agent's stub when

the ticket is folded beneath the same, said agent's stub containing an epitomized caption of the routes for which the ticket can 25 be issued and instructions for issuing the ticket, each coupon bearing the same form number, the name of the issuing line and a suitably designated space for receiving the name of the destination and each having a 30 different caption, the caption of the first coupon containing the name of the initial line and its junction and the caption of each of the other coupons containing the names of the points between which the coupon 35 reads and a reference to the selected line over which the coupon is valid, substantially as described.
